UNITED STATES PATENT OFFICE.

CHARLES S. UPTON, OF NEW YORK, N. Y.

DESIGN FOR A VASE FOR LAMPS, &c.

SPECIFICATION forming part of Design No. 18,471, dated July 17, 1888.

Application filed April 23, 1888. Serial No. 271,646. Term of patent 7 years.

To all whom it may concern:

Be it known that I, CHARLES S. UPTON, a citizen of the United States, residing at the city of New York, county and State of New York, have invented and produced a new and original Design for Vases for Lamps or other Articles, of which the following is a specification, reference being had to the accompanying drawings, forming part hereof.

5 Figure 1 of the drawings shows in elevation my newly-designed vase, both of the handles with which it is provided being in view. Fig. 10 2 is an elevation showing but one of the handles, these views being deemed sufficient to 15 fully illustrate my design.

The leading feature of my design consists in the separate series of vertical or substantially vertical corrugations formed on the body of the vase, said series of corrugations being separated by plane faces or surfaces, and also in providing corrugated or rope handles for the vase.

Referring to the drawings, A represents the body of the vase, which is provided with a top 20 rim or flange, A', and the outwardly-flaring base rim or flange, A".

a a represent a series of corrugations extending from the top to the bottom of the body of the vase and across the top rim, A', and the base rim, A" 30

B B are plane surfaces which separate the series of corrugations *a a*, and these surfaces are provided with flowers or other ornamental figures, as shown.

B' B' are the corrugated or rope handles. 35 They are largest near the center and taper toward the ends in the manner shown, and are attached to the body of the vase on opposite sides thereof.

Having fully described my design, I claim 40 and desire to secure by Letters Patent of the United States—

A design for vases for lamps or other articles having the form and surface configuration herein shown and described.

Signed at the city of New York this 21st day 45 of April, A. D. 1888.

CHARLES S. UPTON.
